Des. 220,932
Patented June 22, 1971

220,932

GARDEN EDGING TOOL OR SIMILAR ARTICLE

Carl B. Jess, N. 4108 Stevens St.,
Spokane, Wash. 99205

Filed July 16, 1969, Ser. No. 18,215

Term of patent 14 years

Int. Cl. D8—01

U.S. Cl. D8—8

FIG. 1

FIG. 2

FIG. 3

FIG. 1 is a left front perspective view of the garden edging tool or similar article embodying my new design; FIG. 2 is a side elevational view thereof; and FIG. 3 is a right rear perspective view thereof.

I claim:

The ornamental design for a garden edging tool or similar article, substantially as shown and described.
